CLAIM

The ornamental design for a display screen or portion thereof with graphical user interface, as shown and described.

DESCRIPTION

FIG. 1 is a front view of a display screen or portion thereof with graphical user interface showing a first image in a sequence of images;

FIG. 2 is a front view of a second image in the sequence; and,

FIG. 3 is a front view of a third image in the sequence. The outermost broken lines shown in the figures are for the purpose of illustrating portions of the display screen or portion thereof and form no part of the claimed design. The remaining broken lines show portions of the graphical user interface that form no part of the claimed design. The appearance of the transitional image sequentially transitions between the images shown in FIGS. 1-3. The process or period in which one image transitions to another forms no part of the claimed design.
